UNITED STATES PATENT OFFICE

2,619,610

EXPULSION GAP LIGHTNING ARRESTER

Tausias Irven Eldridge, Jr., Brookline, and Walter H. Young, Glenside, Pa., assignors to Electric Service Manufacturing Company, Philadelphia, Pa., a corporation of Pennsylvania

Application October 1, 1948, Serial No. 52,318

4 Claims. (Cl. 313—231)

1

Our invention is an electrical protective device or "lightning arrester" providing a substantially unimpeded path from an electric circuit or equipment to ground for lightning or other transient, high potential, electric disturbances, and which quickly suppresses arcs maintained by follow current across gaps ionized by a high potential discharge in passing to ground.

In its preferred form, our invention comprises a series of telescoped, cylindrical walls of gas forming material having spaces between them forming multiple, parallel, cylindrical arc slots of narrow cross-section but extensive area. Each slot is bounded laterally by concentrically curved spaced walls, and hence has, in transverse cross-section the shape of a narrow rectangular slot bent around and spaced from an axis. These parallel slots are intersected by arc electrodes which are connected, meditately or immediately, with line and ground. Preferably, the walls forming the constricted arc slots, and the electrodes intersecting such slots, are enclosed in a non-conducting housing, which also encloses electrodes forming an isolating gap between line and a proximate electrode intersecting the arc slots. The isolating gap prevents application of line voltage to the arc-suppressing elements of the arrester except during actual discharge to ground, and any surface leakage or creepage is over the housing and not through the arrester elements. The enclosure of the isolating gap within the housing prevents any fouling of the gap which, if it occurred, would allow the application of line current to and deterioration of the walls of the arc slots.

The walls forming the arc slots are preferably reinforced by an encircling steel sleeve having its end nearest the isolating gap beveled or flared outward and preferably coated, wholly or partly, with insulation to prevent flash-over to the sleeve from the proximate isolating gap electrode during a discharge to ground.

The concentric cylindrical arc slots are preferably of unequal lengths, the slot of smaller cross-sectional area being the shorter. This tends to divert impulses of steep wave fronts to the outer and longer arc slot and to divert heavy currents of slower rising steepness to the inner, shorter arc slot, and the multiple slots permit the use of walls therefor having gas generating areas which are large relatively to the lengths of the slots of the arrester. The diffusion of the arc or arcs over a large area minimizes the charring or pitting of the gas generating surfaces, and is of particular value in preventing self destruction under discharges involving current

2

magnitudes of very high order because of the multiple paths principle.

The gas generating surfaces of the arc slots are preferably composed of hard fibre or horn fibre, but may be composed of or contain other suitable gas generating substances, such as boric acid, activated by an arc to produce de-ionizing gases tending to suppress an arc.

The principles of our invention, and the best mode in which we have contemplated applying such principles will further appear from the following description and the accompanying drawings illustrating a preferred embodiment of my invention.

15 In the drawings, Fig. 1 is a longitudinal sectional view of a lightning arrester or protective device embodying our invention; Fig. 2 is a transverse sectional view taken on the line 2—2 of Fig. 1; Fig. 3 is a transverse sectional view taken on the line 3—3 of Fig. 1; Fig. 4 is an enlarged broken perspective view of the ground electrode at the bottom of the arc slots; Fig. 5 is an exploded, longitudinal sectional view of the electrode shown in Fig. 4 and of the core and tube to be seated therein; Fig. 6 is a transverse sectional view taken on the line 6—6 of Fig. 5; and Fig. 7 is a fragmentary part sectional view illustrating a modification of the flaring and coating of the top of the reinforcing sleeve.

30 The embodiment of our invention illustrated in the drawings comprises an external housing composed of a cylindrical, wet-process porcelain body 1 having one end closed by a porcelain plug 2 glazed into the body. The opposite end of the housing is countersunk to form a seat 3 for the flanged edge 4 of a conducting cup 5 which may be provided with a hollow depending terminal boss 6 for the attachment of a ground 7. The cup 5 is secured against the seat 3 by a plastic seal 8 and non-plastic cement 9.

40 A cylindrical hard fibre shell 10 has its end threaded into the threaded cup 5 and is encircled by a steel, seamless, reinforcing sleeve or shield 11 which may be staked to the cup 5 and is therethrough connected to the ground. The sleeve 11 projects along the shell 10 beyond the portion thereof containing the arc quenching slots and upper arc electrode hereinafter described.

45 As illustrated in Fig. 1, the upper end of the sleeve 11 is flared outward by belling the rim 12 thereof to form a channel which may be filled with a ring of non-conducting sealing material 13, such as resin. In the modification illustrated in Fig. 7, the upper end of the sleeve 11 is flared by beveling the edge 12' which may be surrounded

by a non-conducting ring 13'. The flaring of the upper end of the sleeve 11 away from the tube 10 greatly decreases the liability to flashover.

A cylindrical electrode 14 is seated in the cup 5 within the shell 10 and has a peripheral wall 15 containing the countersink 16 at one end thereof and diametral slots 17 which communicate, through an aperture 19 in the bottom of the electrode, with a discharge passage 20 through the terminal boss 6.

A core 21 is seated on a non-elastic metallic washer 22 in the countersink 16; the core preferably consisting of a filler rod 23 and a fibre tube 24.

A fibre tube 25 is telescoped over the core 21 and spaced slightly therefrom and from the inner wall of the shell 10 to form multiple, concentric, cylindrical arc slots each having walls of gas-forming material concentric with but spaced from one another.

The arc slots are intersected, at the upper ends thereof, by an electrode 26 making a close fit with the inner wall of the shell 10 intermediate the ends thereof. The electrode 26 has a peripheral flange 27 closely encircling and centering the reduced upper end of the tube 25. An elastic gasket 28 and a felt gasket 29 are interposed between the end of the tube 25 and the electrode 26 and lie in a channel between the flange 27 and boss 30 of the electrode. The boss 30 extends into the end of the tube 25 and presses against the top of the core 21 to press it tightly against the washer 22. The electrode 26 may be secured to the core 21 by a screw 31.

The head of the screw 31 is housed within a conducting tube 32 which is telescoped over the boss 33 on the top of the electrode 26.

A conducting plug 34 is threaded into the upper end of the shell 10, with its periphery well inward from the periphery of the tube 10, and has a boss 35 extending into the tube 32. By tightening up the plug 34 in the shell 10, a desired degree of pressure may be applied to the electrode 26, tube 25, core 21 and electrode 14 to prevent axial or rotary movement of these parts and secure their concentricity to one another.

An electrode 36, seated in the plug 34, and an electrode 37, carried by the end closure 2, form an isolating gap 38 normally isolating the arc quenching elements of the arrester from line but providing a path to ground for impulse surges due to lightning or the like.

The electrode 37 has a shank 39 which passes through an aperture 42 in the closure 2 and the joint between the shank and closure is sealed by the fibre gasket 40 and 41 which are squeezed by the electrode 37 and gasket cup 43 when the nut 44 is drawn up on the shank 39. The nut 44 may be provided with a serrated surface complementary to the wire clamp 45 for gripping the line conductor 46 when the nut 47 is tightened up. A hollow cap 48 is detachably connected with the shank 39 to provide a weather shield for the line connection assembly.

The interior of the housing 1 is ventilated through ventilating apertures 49 through the flange 4 and the cement 9.

The arrester may be mounted in any suitable position adjacent to a circuit to be protected by a metal bracket 50 encircling the housing 1 intermediate the ends of the reinforced sleeve 11; the bracket 50 being spaced from the line terminal of the arrester by the corrugated area 51 of the surface of the housing 1.

When a lightning surge or other transient high

potential electric disturbance reaches the section of the line with which the line terminal 39 is connected through the conductor 46, it is discharged across the isolating gap 38, through the electrode 36, plug 34, conductor 32, electrode 26, through one or both of the arc slots, electrode 14, terminal boss 6 and conductor 1 to ground. The arc through the arc slots quickly generates large volumes of de-ionizing gas which extinguishes the arc maintained by follow current at or before the next zero point of the cycle of the alternating dynamic current. The generated gas is expelled from the arc slots through the electrode slots 17 and passages 19 and 20, away from the ground conductor 1.

An arrester constructed in accordance with our invention has a low impulse spark-over voltage, a high discharge current capacity and a high dynamic failure voltage and arc suppressive characteristics. Under standard test conditions, our arrester will cut off flow of 60 cycle dynamic follow current to ground within approximately an eighth of a cycle after the inception of a breakdown due to surge current, and will discharge without appreciable damage to itself test current of very high magnitudes, e. g. of the order of 180,000 amperes, and restore itself to its original operating condition.

The area of gas generating material is large proportionately to the length or volume of the arc slots and the arc is so distributed between the parallel slots that impairment of the walls of the slots is minimized. The impulse breakdown is inherently low and is further lowered by the conductive connection of the steel shield 11 to ground and consequent balancing which is accomplished by the capacitances between line and ground terminals.

Having described my invention, I claim:

1. An electrical protective device comprising a non-conducting external housing, a conducting cup seated in one end of said housing, a tubular shell seated in said cup, a reinforcing metallic sleeve encircling said shell and having one end secured to said cup and its other end flared, an electrode seated in said cup within said shell and having an apertured rim and a central socket, a core seated in said socket, a tube supported by the rim of said electrode and encircling said core, said core, tube and shell forming multiple concentric cylindrical arc slots having walls of material that generates gas in the presence of an arc and are concentric with but spaced from one another, an electrode intersecting said arc slots and having a boss engaging said core and a head engaging said tube, a conductor connected with said last named electrode, a plug threaded in said shell against said conductor and pressing said core, tube and electrodes axially, said plug having a member forming an electrode, a closure for the other end of said non-conducting housing, and an electrode carried by said closure and forming an isolating gap with said electrode last named.

2. An electrical protective device comprising a non-conducting external housing, a tubular shell within said housing and having an electrode intermediate the ends thereof and an electrode at each end thereof, a conducting member connecting the intermediate electrode with one of the end electrodes, a core and a tube interposed between the intermediate electrode and the other end electrode and forming with said shell parallel concentric cylindrical arc slots each having walls of material that generates gas in the pres-

ence of an arc and are concentric with but spaced from one another, and an electrode at one end of the housing and complementary to the first named electrode at an end of said shell and forming therewith an isolating gap.

3. An electrical protective device comprising a conducting cup, a tubular shell seated in said cup, an electrode at each end of said shell and an electrode intermediate the ends of said shell, a reinforcing metallic sleeve encircling said shell and conductively connected with said cup and having its end remote from said cup flared outwardly, a core and a tube within said shell between said intermediate electrode and one end electrode, said core, tube and shell forming parallel cylindrical arc slots each having walls of material that generates gas in the presence of an arc and spaced from one another, and a conductor within said shell and mechanically spacing and electrically connecting said intermediate electrode and the other of said end electrodes.

4. An electrical protective device comprising a hollow tubular shell of insulating material, an electrode seated in one end of said shell and having a peripheral wall countersunk at one end and diametral slots communicating with an axial gas venting passage through the other end of said electrode, a core seated in the countersunk end of said electrode, a tube seated on the slotted end of the peripheral wall of the electrode, said

core and tube forming an arc slot having walls of gas forming material spaced from one another, and an electrode intersecting said arc slot at the end of said core and tube remote from said first electrode to support said core and tube in concentric relation, said slots and axial passage providing an escape path for gases resulting from an arc between said electrodes in said arc slot.
